(57) **CLAIM**

The ornamental design for a watch with interchangeable face, as shown and described.

DESCRIPTION

FIG. 1 is a front elevational view of the watch with interchangeable face showing my new design;

FIG. 2 is a rear elevational view of the watch with interchangeable face thereof;

FIG. 3 is a left-side elevational view of the watch with interchangeable face thereof;

FIG. 4 is right-side elevational view of the watch with interchangeable face thereof; and,

FIG. 5 is a top plan view of the watch with interchangeable face thereof;

The broken lines shown in FIG. 1 are for illustrative purposes only and form no part of the claimed design.
